UNITED STATES PATENT OFFICE.

LOUIS CHARLES GREVEMBERG, OF CALUMET, LOUISIANA.

SETTLING APPARATUS.

1,150,360.

Specification of Letters Patent.

Patented Aug. 17, 1915.

Application filed February 25, 1915. Serial No. 10,649.

To all whom it may concern:

Be it known that I, LOUIS C. GREVEMBERG, a citizen of the United States, residing at Calumet, in the parish of St. Mary and State of Louisiana, have invented a new and useful Settling Apparatus, of which the following is a specification.

This invention relates to settlers or separators especially designed for use in the treatment of juices and liquids such as molasses and syrups, one of the objects of the invention being to provide a settler made up of units so constructed and arranged that, during the flow of the liquid therethrough, 15 gases and vapors carried by the liquid are free to rise promptly from the liquid to the external atmosphere or to a vacuum pump provided therefor, whereby their disturbing influence of the light and flocculent precipitates is greatly minimized, due to their rapid elimination from the volume of liquid.

Another object is to provide apparatus so constructed and arranged that the sediment carried by the liquid is precipitated 25 through the liquid for a short distance only before coming to their point of discharge so that they are thus quickly removed from the currents of the liquid and can thus be more readily drawn off than otherwise.

30 A further object is to provide apparatus of this character which operates efficiently to clear the treated liquids because of the immediate removal of gases and vapors from said liquids upon entering the apparatus and the prompt settling of the sediment out of the path of the moving liquid.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 45 within the scope of what is claimed, without departing from the spirit of the invention.

In the accompanying drawings the preferred form of the invention has been 50 shown.

In said drawings: Figure 1 is a side elevation of the apparatus. Fig. 2 is a rear elevation of the separating tanks, the supporting structure being removed. Fig. 3 is an enlarged longitudinal section through one

of the tanks, the same being placed in a horizontal position for convenience of illustration.

Referring to the figures by characters of reference 1 designates an inclined tank preferably cylindrical and provided, at the lower end of its bottom with an outlet 2 for the discharge of any sediment which may accumulate within the tank. The upper portion of the tank is open to the external atmosphere or, if desired, a pipe 3 may connect the interior of the upper portion of the tank to a vacuum pump or the like.

Any desired number of tanks 1 may be 70 used in the apparatus, these tanks being supported in inclined positions by any suitable structure indicated generally at 4. Each of the tanks is provided near the lower end thereof with an inlet pipe 5 provided 75 with a T-shaped discharge nozzle 6 disposed in a plane extending longitudinally of the tank, one of the outlets of the nozzle extending between the inlet pipe 5 and the lower end of the tank as shown. Another or outlet pipe 7 is arranged within the tank near the top thereof and is also provided with a T-shaped portion 8 which constitutes a double outlet for the liquid contents of the tank. A supply pipe 9 extends to the inlet pipe 5 80 of the first tank and a connecting pipe 10 extends from the outlet pipe of said first tank to the inlet pipe of the second tank. This arrangement is continued throughout 85 the length of the apparatus, the last tank 90 of the series having its outlet pipe arranged to discharge the treated liquid wherever desired.

The drain pipes 2 are preferably provided with valves 11 of any construction desired 95 for controlling the outflow of sediment.

In using the apparatus, the molasses, syrup or other liquid to be treated is directed through the pipe 9 into the inlet pipe 5 of the first tank and flows through the 100 nozzle 6. By referring particularly to Fig. 1 it will be seen that as soon as the liquid enters the nozzle 6, any heavy sediment contained therein will promptly gravitate a short distance to the lowermost portion of 105 the tank while at the same time, any gases or vapors commingled with the liquid will be free to escape upwardly within the tank 1 and to the external atmosphere or to the vacuum pump by way of the pipe 3. This 110

prompt release of the gases and vapors from the liquid reduces to the minimum their disturbing influences on the light and flocculent precipitates contained within the liquid. As the sediment or precipitates in the liquid gravitate but short distances to the lowermost portion of the tank, they are promptly removed from the current of the inflowing liquid so that the danger of this sediment or precipitate being carried out of the tank with the outflowing liquid is minimized. As the liquid rises within the tank it flows outwardly through the pipe 7 into pipe 10 to the inlet pipe 5 of the next tank 1 where the foregoing operation is repeated, it being understood that after the liquid has passed through a series of tanks such as described, the separation of gases, vapors, and precipitates or sediment is completed and a pure product produced.

It is to be understood of course that the pitch of the tanks can be varied as to provide an exposed liquid surface in the tanks of any desired area. Obviously the greater the area of the exposed surface, the more rapid and efficient will be the separation of the gases and vapors from the liquid.

The several units can be connected by a pipe connecting the pipes 5, whereby clear liquid can be withdrawn from the apparatus in the event of extended delays. This pipe is shown at 11. It is to be understood that the form and location of the connection 11 can be varied or said connection can be entirely dispensed with if desired.

What is claimed is:—

1. Separating apparatus of the class described, including an inclined tank having a sediment outlet in its lowest portion, means for directing liquid into the tank at a point adjacent said outlet, and means for withdrawing the liquid from the tank at a point adjacent the top thereof, there being an out-

let above said last named means for the escape of gas and vapor.

2. Apparatus of the class described, including a series of inclined tanks each having a liquid inlet adjacent the lowest portion thereof and a liquid outlet near the top thereof, the liquid outlet of one tank being in communication with the liquid inlet of the next adjoining tank, all of the tanks having outlets at their upper end for the escape of gas and vapor, and means at the lowest portion of each tank for withdrawing sediment from the tank.

3. Apparatus of the class described, including a series of inclined tanks each having a liquid inlet adjacent the lowest portion thereof and a liquid outlet near the top thereof, the liquid outlet of one tank being in communication with the liquid inlet of the next adjoining tank, all of the tanks having outlets at their upper ends for the escape of gas and vapor, and means at the lowest portion of each tank for withdrawing sediment from the tank, said means being disposed under and close to the liquid inlet.

4. Apparatus of the class described, including an inclined tank having a valved sediment outlet in its lowest portion, an inlet nozzle in the lower portion of the tank and close to and above the sediment outlet for directing liquid into the tank, a liquid outlet pipe in the upper portion of the tank, there being an outlet in the upper portion of the tank and above the liquid outlet for the escape of released gas and vapor.

In testimony that I claim the foregoing as my own, I have hereto affixed my signature in the presence of two witnesses.

LOUIS CHARLES GREVEMBERG.
